(57) **CLAIM**

The ornamental design for a part of a display screen stand as shown and described.

DESCRIPTION

Figure 1.1 is a front, top and right side perspective view of a part of a display screen stand, showing our new design; Figure 1.2 is a rear, top and right side perspective view thereof;

Figure 1.3 is a front elevation view thereof;

Figure 1.4 is a rear elevation view thereof;

Figure 1.5 is a left side elevation view thereof, the right side elevation view being a mirrored image thereof;

Figure 1.6 is a top plan view thereof;

Figure 1.7 is a bottom plan view thereof;

Figure 1.8 is an enlarged rear, top and right side perspective view thereof, taken from Figure 1.2;

Figure 1.9 is an exploded front, top and right side perspective view thereof;

Figure 1.10 is an enlarged front, top and right side perspective view thereof, shown in an alternate position;

Figure 1.11 is a left side elevation view thereof, shown in an alternate position;

Figure 1.12 is a top plan view thereof, shown in an alternate position;

Figure 1.13 is a rear, top and right side perspective view thereof, shown in an environment of use; and

Figure 1.14 is another rear, top and right side perspective view thereof, shown in an environment of use and in an alternate position.

The evenly-spaced broken lines shown in Figures 1.1-1.12 illustrate portions of the part of a display screen stand that form no part of the claimed design. The broken lines illustrating the display screen in Figures 1.13 and 1.14 are environment, while the remaining broken lines in Figures 1.13 and 1.14 illustrate portions of the part of a display screen stand that form no part of the claimed design. The (Continued)

dash-dot-dash broken lines shown in Figures 1.2, 1.8 and 1.10 illustrate the bounds of the enlarged portions of the part of a display screen stand.
